DESCRIPTION

(56) **References Cited**

FIG. 1 is a front elevational view thereof of a digital video disc recorder showing my new design;
FIG. 2 is a rear elevational view thereof;
FIG. 3 is a right side elevational view thereof;
FIG. 4 is a left side elevational view thereof;
FIG. 5 is a left top plan view thereof;
FIG. 6 is a bottom plan view thereof;
FIG. 7 is a perspective view of the top, front and right side elevational view thereof; and,
FIG. 8 is a perspective view similar to FIG. 7 with the disc holder extended.
